SPARK PLUG

Richard J. Burtnett, Baltimore, Md.

Application July 2, 1935, Serial No. 29,544

3 Claims. (Cl. 123—169)

The object of this invention is to so construct the spark plug that the heat will be conducted to the engine body in a quick and efficient manner to thereby not only prevent pre-ignition at 5 the burning point, but also protect the porcelain body against excessive heat and further to provide means whereby the sparking electrodes are more efficient in action and more durable, as well as more readily replaceable when worn, as 10 more fully hereinafter set forth.

In the drawing annexed;

Fig. 1 is a longitudinal sectional view of a spark plug showing my preferred construction:

Fig. 2 is a bottom view of the plug, partly in horizontal section;

Fig. 3 is a horizontal section on the line 3-3 of Fig. 1:

Fig. 4 is a view partly in side elevation and partly in vertical section showing the form of the plug without the expander disk; and Fig. 5 is a detail view of the inner end of the

25 Referring to Figs. 1 and 2 of the drawing, by reference characters, 10 designates the metal body of the plug which is constructed as usual, and 11 is the usual porcelain rod removably fastened in the tubular body 10 in the usual manner and having the usual metal electrode supporting rod 12 extending longitudinally through it.

36 through it.
The extreme inner end of the conductor 12
has detachably attached to it a split ring 13
which forms the central electrode. This ring is
adapted to be snapped off and onto a headed pro-
35 jection 14 formed on the extreme inner end of
the rod 12. Surrounding the annular electrode
13 is another annular, split ring electrode 15
which is adapted to be snapped into and out of
an annular groove formed in the interior of the
40 plug body 10 at a point coincident with the cen-
tral electrode 13, the two electrodes being pro-
portioned and separated so as to produce an an-
nular spark gap between them. In practice,
45 sparking may occur at any point around the fac-
ing circumferences of the electrodes, taking, of
course, the easiest path. From time to time, the
point of sparking changes, with the result that
in time sparking or arcing occurs entirely around
50 the rims of the electrodes. In this way, the elec-
trodes will endure a great length of time as com-
pared with the ordinary single sparking point
device. Also, this arrangement of sparking de-
vices renders fouling a remote contingency.

The inner open end of the body 10 is closed 55 by means of a disk 16 which convexes inwardly

and is provided with a plurality of holes 17. Fuel mixture enters the spark chamber only through these holes 17, and by proportioning these holes properly, the ignition pressure within the sparking chamber may be kept down below that of the ignition pressure in the cylinder, thereby reducing the likelihood of fouling the spark electrodes by the formation of carbon within the sparking chamber, and by the tendency to cause outwardly moving jets through the holes 17 as the pressure 10 on the working stroke of the engine decreases. The main purpose, however, of the dome-like disk 16 is to provide an efficient means for conducting the heat directly into the body 10 and thence to the engine body. The edge of the disk 15 16 is held in hard metallic contact with the inner end of the body 10 and this insures quick distribution of the heat into the tubular body 10.

For the purpose of detachably attaching the dome-like disk 16 to the body 10, I form in the interior of the body 10 at its extreme inner end an under-cut annular groove, and I shape the annular edge of the disk 16 so as to fit snugly therein, when the said annular edge is expanded by means of an expanding disk 18 which is clamped between the edge of the disk 16 and a downwardly facing shoulder 19 formed by the groove in the body 10.

It will be understood that the disk or ring 18 is of such size that when the cup 16 is forced into the under-cut groove, the annular edge of the ring 18 will cause the rim or edge of the cup to expand outwardly into the under-cut groove and thus lock not only the cup 16, but also the disk 18 solidly in place. It will be understood that the disk 18 will be of such size as to pass freely into the under-cut groove and against shoulder 19 and also that before expanding the rim of cup 16 said rim will pass freely into the groove, so that the parts may be readily assembled. The disk 18 is provided with suitable openings to permit fuel to reach the sparking electrodes. The cup-like disk 16 is slightly flexible and expandable to thus enable it to be solidly fitted into the under-cut groove; and to remove the cup-like disk 16, it is necessary to merely use an appropriate tool; for instance, I may insert a punch down through the central bore of the plug and push it out of the under-cut groove.

the plug and push it out of the under-cut groove. It will be observed that the cup it attached directly to the barrel of the spark-plug proper and that therefore the heat will be dissipated to the engine body with a maximum of speed. 50

In Fig. 4, I omit the expander ring 18 and expand the edge of the cup by other means, as for 55

instance by beveling the shoulder 19 outwardly and upwardly.

I propose using metals of different conductivity for the cups 16; for instance, I may use copper for high pressure motors to get the greatest heat conductivity possible; with standard motors, I may use brass cups; and for "cold" low-pressure motors, I may use steel.

I claim:

1. A spark plug embodying a plug body whose inner end is grooved interiorly and a cup-like perforated metal disk covering the open end of the plug body and enclosing the sparking ele-

ments and having its annular edge fitted into said groove.

2. The structure recited in claim 1, said groove being under-cut and the annular edge of the disk being expanded to fit into said under-cut groove.

3. The structure recited in claim 1, the metal disk being in the form of an inwardly-convexing cup and being expandable at its rim portion, and an open expander disk whose annular edge bears against the expandable rim portion of the cup to lock the same in the under-cut groove.

RICHARD J. BURTNETT.
